UNITED STATES PATENT OFFICE.

CHARLES LAWRENCE STOKES, OF LOS ANGELES, CALIFORNIA.

METHOD AND MEANS FOR APPLYING ENGINE EXPLOSION PRESSURE.

Application filed October 15, 1924. Serial No. 743,818.

My invention relates to improvements in utilizing the hot gases of an internal combustion engine under explosion pressure, wherein the expanding gases just prior to being exhausted from the engine are trapped in order to utilize the work remaining therein.

Another object of my invention is to utilize the waste heat from exhaust gases under pressure in the operation of an internal combustion engine.

Another object of my invention is to provide a constant volume engine.

Another object of my invention is to provide a constant compression engine.

Another object of my invention is to provide a constant volume engine which may also be a supercharged constant volume engine.

Another object of my invention is to provide a supercharging device for an internal combustion engine which operates under constant volume.

Another object of my invention is to provide a constant compression supercharging device for an internal combustion engine.

Another object of my invention is to provide stratification of the charge in a constant volume engine.

In general the further objects of my invention are to provide means of utilizing waste exhaust gases under pressure for vaporizing liquid fuel, and supercharging an internal combustion engine.

This invention embodies improvements on my Patent 1,308,560 and also improvements on a copending application executed of even date herewith.

Referring to the drawings in which the same numbers indicate like parts:—

Fig. 1 is a vertical section, partly in elevation, of an engine embodying my improvements.

Fig. 2 is a transverse section along the lines 2—2 of Fig. 1.

Fig. 3 is a transverse section along the lines 3—3 of Fig. 1.

Fig. 4 is a transverse section along the lines 4—4 of Fig. 1.

An internal combustion engine 1, of the type described in my aforesaid patent, is provided with a cylinder 2 surrounded by a water jacket 3. Within the cylinder 2 is reciprocated a sleeve valve 4 having at its end an annular piston skirt 5 which recip-

rocates in an extension of the engine crank case.

The usual piston 6 is adapted to be reciprocated within the sleeve 4 and both 4 and 6 are reciprocated by the turning of the engine 60 crank shaft 7, the piston 6 being actuated by a connecting rod 8 and the sleeve 4 being actuated by a connecting rod 9 operated through the movement of an eccentric 10.

It will be noted here that the piston 6 and 65 the sleeve 4 are reciprocated in opposite phase to the end that with the proper design as to the throws and weights of the piston and sleeve together with their connecting rods, a balanced couple will result in each 70 individual cylinder of a multi-cylindered engine.

A part of the water jacket 3 is segregated to form a vaporizing, and supercharging chamber 11 and a hollow rotary throttling 75 and distributing valve 12 is passed therethrough providing communication interiorly thereof with a compression space 13 at the upper end of 5.

The valve 12 rotates, closely at its bottom, in the lower portion of 11 and also centrally in a web 14 and at its upper end in a web 15 and valve 12 contains a lower port 16 adapted to register with a passage 17 and an upper port 18 adapted to register with a passage 19.

A series of slots 20 also serve to pass a mixture of air and liquid fuel, or air and gases, from a carburetor 21 through a manifold 22 and past a rotary valve 23 to the interior of 12, so that a combustible mixture 90 may be alternately drawn into 13 and forced to the interior of 4 at the proper moment.

The carburetor 21 is provided with a liquid feeding pipe 24, an air passage 25 and a gas feeding pipe 26 to the end that the proper mixture of liquid fuel and air, or gas and air, may be provided for operating the engine 1 as desired.

The cylinder 2 is provided with upper and lower grooved passages 27 and 28 respectively adapted to communicate respectively with the passages 19 and 17 and 2 is also provided with an intermediate grooved passage 29 adapted to communicate with an exhaust port 30.

The sleeve 4 is provided with an upper belt of ports 31 and a lower belt of ports 32 adapted to register at predetermined periods with the passages 27 and 28 respectively and 4 is also provided with an intermediate belt 110

of ports 33 adapted to register with the passage 29.

The outer end of 2 and 4 is closed by a water jacketed cylinder head 34 adapted to be closed by a spark plug in orifice 35 and an extension 36 is bolted to 34 for guiding and retaining valve 12 in position by means of a spring 37, the valve 12 being rotated by a throttle 38 for increasing, or decreasing 10 the speed of the engine. The rotary throttle valve 23 is driven from the crank shaft 7 at engine speed by means of a chain 39, or other suitable device, to the end that the manifold 22 will be completely open and 15 completely closed during one revolution of 7.

A slanting passage 40 passes through 2 for providing communication between 11 and the interior of 4 and the proportionate opening of 40 may be governed by the movement 20 of 12 by means of a control 41 adjustably clamped to the valve 12, see Fig. 4, access to which may be obtained by the removal of a cover plate 42.

It will be noted that the belts of ports 31, 25 32 and 33 are constructed with walls at an angle from the horizontal where such ports pass through the sleeve 4 for communicating respectively with passages 27, 28 and 29, this angle serving to direct the entering combustible gases particularly towards the inner 30 end of 34 and the top of piston 6 in order to completely scavenge the interior of 2 and also in the case of the ports 33 to provide a straight passageway from the interior of 2 35 to the interior of 11 as will be later described.

As shown in Fig. 1 the piston 6 is at the bottom of its stroke and the sleeve 4 and piston 5 are at the top of their strokes, in 40 which position it is provided that the belts of ports 31, 32 and 33 give complete access respectively to the passages 27, 28 and 29. The engine being described is of a two cycle type and therefore in the particular position illustrated the charge of combustible mixture which has previously been drawn from 21 through 22, 20 and 12, will have been compressed in 13 and 12 and therefore if the ports 16 and 18 are in full register with the 45 passages 17 and 19 respectively, it will be seen that the combustible charge compressed in 12 will have passed through 31 and 32 to the interior of 2, thus forcing exhaust gases through 33 and 30, it being understood that 50 in this position the valve 23 would be closed in order to maintain the gas under pressure in 12.

As is usual in two cycle practice and as is explained in my aforesaid patent the belt 60 of exhaust ports 33 is arranged to register with the passage 29 a slight predetermined distance ahead of the registry of the belts of ports 31 and 32 with the passages 27 and 28 respectively in order that the exhaust 65 gases will be relieved of their pressure

slightly in advance of the incoming charge of fresh combustible gas so that such fresh gas will have but atmospheric pressure to overcome when injected by 5 into the interior of 4.

If now it be assumed that 6 is starting to move on its compression stroke, 5 will be coming down on its suction stroke and valve 23 will be opening for the admission of further combustible mixture through 12 into 13 and the belts of ports 31, 32 and 33 will be moving down for closing the passages 19, 17 and 29 respectively to the end that when 6 is moved a predetermined distance the passages 19, 17 and 29 will be closed from the interior of 2 and therefore the piston 6 may compress this fresh charge of gas in the interior of 4 to its full capacity, which gas is then fired at the correct position of 6 for imparting a power impulse to 6.

Let it be assumed that this firing position is when 6 is at its upper limit of travel and 5 is at its lower limit of travel, in which case it may be seen that 13 will then be full of a 50 fresh charge of combustible gas and the valve 23 will be just closed.

The piston 6 then descending on its power stroke, and at a predetermined position in that power stroke, and also owing to the fact that the sleeve 4 is ascending, one of the ports 55 in the belt 33 will come into registry with the passage 40 and when said port is uncovered by the piston 6 a portion of the gases under explosion pressure will pass into 11 and will be trapped therein because the sleeve 4 will continue its upper movement to close off the passage 40 and thereafter will connect the belt of ports 33 for relieving the balance of the pressure of the exploded gases and, as already explained, thereafter the fresh compressed 105 charge in 13 and 12 will scavenge the interior of 4 of the balance of the exhaust gases.

The exhaust gases under pressure now trapped in 11 will be then injected into the interior of 4 when piston 6 next starts on its upstroke and sleeve 4 starts on its downstroke because the belt of ports 33 will first come out of registry with the passage 29 and will thereafter register with the passage 40 so that the 110 exhaust gases under pressure will be directed towards the head of piston 6 and thereby, by their weight, increase to any desired degree, the compression to which the combustible gas in 4 may be subjected. Immediately after the exhaust gases are thus injected 115 through 40, it will be seen that the upward movement of 6 will cover the belt of ports 33 and also the passage 40 thus preventing any of the charge within 4 from being forced into 120 11.

Preferably I arrange the sizes of the belts of ports 31, 32 and 33 and also the size of passage 40 in conformity with the bore and stroke of the engine so that the exhaust gases under pressure will be trapped in 11 at a prede- 125 130

5   terminated degree of revolution of 7 from upper dead center and this degree of revolution may be varied to get a desired effect but as an illustration it will be seen that if a port of the belt 33 is in registry with 40 at about 120° of revolution exhaust gases will be trapped in 11 at varying degrees of pressure depending on the amount of combustible charge admitted through 12. From 120° of revolution on, it will be seen that the sleeve 4 will 10 close the passage 40 and thereafter almost immediately the belt of ports 33 will register with 29 and the movement of sleeve 4 will then restrain the exhaust gases in 11 until the piston 6 travels about 60° from lower dead center when the downward movement of sleeve 4 will uncover the passage 40 again and thereafter, the exhaust gases being quickly injected into 4, the piston 6 will cover the belt 15 of ports 33 and thereby also the passage 40.

20   If liquid fuel and air is being supplied from 21, it will be seen that the heat of the exhaust gases trapped in 11 will serve largely to vaporize any unvaporized liquid fuel passing through 12 and this is highly desirable in order to prevent unvaporized fuel passing into 13 and consequently the heat of the exhaust gases is extremely useful for this purpose, wherein valve 12 forms a "hot-spot".

25   30   The amount of exhaust gas trapped in 11, and consequently the pressure under which it is retained therein, may be largely controlled by the action of 41 due to the movement of 12 and the control 41 may be adjusted for various operations of engine 1 as is desired. For instance, if it be desired to maintain constant volume, with or without supercharge, in the interior of 4, the control 41 may be arranged to open 40 to the fullest extent when 35 the ports 16 and 18 are at minimum registry with the passages 17 and 19 respectively. Thereafter when 16 and 18 are in full registry with 17 and 19 respectively, the control 41 will have partially closed the passage 40, so that in this manner a compensated compression is obtained. When 16 and 18 are partially closed it will be seen that a lower explosion pressure will result in 4 but when 16 and 18 are fully open a maximum explosion pressure will result in 4 and therefore it can be seen that a regulation for constant volume may be obtained by the setting of the control 41.

40   45   At the same time I do not limit myself to this particular setting because some designers of engines do not prefer constant volume with variable speed but require only supercharging on full load, or as the load approaches the maximum, and therefore in such cases it can be seen that 41 may be so arranged to operate in a fashion opposite to that already described.

50   55   Referring particularly to the operation of throttle 12, it may be seen that, if 12 is assumed to be operative in clockwise fashion, the ports 18 and 16 will register with the pas-

5   6   7   8   9   10   11   12   13   14   15   16   17   18   19   20   21   22   23   24   25   26   27   28   29   30   31   32   33   34   35   36   37   38   39   40   41   42   43   44   45   46   47   48   49   50   51   52   53   54   55   56   57   58   59   60   61   62   63   64   65   66   67   68   69   70   71   72   73   74   75   76   77   78   79   80   81   82   83   84   85   86   87   88   89   90   91   92   93   94   95   96   97   98   99   100   101   102   103   104   105   106   107   108   109   110   111   112   113   114   115   116   117   118   119   120   121   122   123   124   125   126   127   128   129   130

sages 19 and 17 respectively at different periods. This arrangement is made in order to provide for the longer travel of combustible gas from 13 through 12 to 18 and also to provide for stratification of the charge forced into 4 at light loads whereby the combustible gas may only pass through 18 and thereby is easily fired because the same will scavenge the sleeve 4 only in the vicinity of the spark plug and likewise will be held by compression only in the vicinity of the spark plug. By doing this great flexibility and other desirable features may be obtained in the operation of a two cycle engine, more particularly with the type herein illustrated and described in which a minimum travel for the scavenging gases is provided.

5   6   7   8   9   10   11   12   13   14   15   16   17   18   19   20   21   22   23   24   25   26   27   28   29   30   31   32   33   34   35   36   37   38   39   40   41   42   43   44   45   46   47   48   49   50   51   52   53   54   55   56   57   58   59   60   61   62   63   64   65   66   67   68   69   70   71   72   73   74   75   76   77   78   79   80   81   82   83   84   85   86   87   88   89   90   91   92   93   94   95   96   97   98   99   100   101   102   103   104   105   106   107   108   109   110   111   112   113   114   115   116   117   118   119   120   121   122   123   124   125   126   127   128   129   130

Thus it will be seen that if on light loads the rotation of 12 causes 18 to be only partly open, a predetermined amount of combustible gas only will pass through 19 and 31 for scavenging the upper part of the interior of 4 close to the spark plug orifice 35 and this amount of gas, being stratified, will fire easily to obtain the desired effect for a light load because the port 16 will be entirely closed from registry with the passage 17.

5   6   7   8   9   10   11   12   13   14   15   16   17   18   19   20   21   22   23   24   25   26   27   28   29   30   31   32   33   34   35   36   37   38   39   40   41   42   43   44   45   46   47   48   49   50   51   52   53   54   55   56   57   58   59   60   61   62   63   64   65   66   67   68   69   70   71   72   73   74   75   76   77   78   79   80   81   82   83   84   85   86   87   88   89   90   91   92   93   94   95   96   97   98   99   100   101   102   103   104   105   106   107   108   109   110   111   112   113   114   115   116   117   118   119   120   121   122   123   124   125   126   127   128   129   130

Thereafter if it be desired to increase the speed of the engine, 18 will further open until at least one half a charge for the entire cylinder may be admitted through 18 and as the speed of the engine is increased by the rotation of 12, the port 16 will come further and further into registry with the passage 17 until finally a complete charge will fill the interior of 4.

5   6   7   8   9   10   11   12   13   14   15   16   17   18   19   20   21   22   23   24   25   26   27   28   29   30   31   32   33   34   35   36   37   38   39   40   41   42   43   44   45   46   47   48   49   50   51   52   53   54   55   56   57   58   59   60   61   62   63   64   65   66   67   68   69   70   71   72   73   74   75   76   77   78   79   80   81   82   83   84   85   86   87   88   89   90   91   92   93   94   95   96   97   98   99   100   101   102   103   104   105   106   107   108   109   110   111   112   113   114   115   116   117   118   119   120   121   122   123   124   125   126   127   128   129   130

As already stated, it is desirable in any case to proportion the opening of 18 with regard to the opening of 16 to take care of the longer distance of travel of the gases from 13 under all conditions and this system is more especially effective because it will be noted that the combustible gas drawn into 13 is maintained in 12 under constant compression which is due to the location and construction of the ports 18 and 16 already described.

5   6   7   8   9   10   11   12   13   14   15   16   17   18   19   20   21   22   23   24   25   26   27   28   29   30   31   32   33   34   35   36   37   38   39   40   41   42   43   44   45   46   47   48   49   50   51   52   53   54   55   56   57   58   59   60   61   62   63   64   65   66   67   68   69   70   71   72   73   74   75   76   77   78   79   80   81   82   83   84   85   86   87   88   89   90   91   92   93   94   95   96   97   98   99   100   101   102   103   104   105   106   107   108   109   110   111   112   113   114   115   116   117   118   119   120   121   122   123   124   125   126   127   128   129   130

The compression of gas in 12 may be designed for any predetermined maximum and therefore no matter how wide open the ports 18 and 16 may be, the same degree of compression will prevail in 12 prior to the uncovering of passages 19 and 17 by the belts of ports 31 and 32 respectively. In this manner more effective operation is maintained and the throttle 12 controls the passage of combustible mixture through the carburetor 21 because it will be seen that if a minimum amount of combustible gas is being expelled from 12, a minimum suction thereafter will prevail for application to the carburetor 21. In other words, a constant supply of combustible gas is maintained for effective use at the proper time under constant compression in 12 and 13.

5   6   7   8   9   10   11   12   13   14   15   16   17   18   19   20   21   22   23   24   25   26   27   28   29   30   31   32   33   34   35   36   37   38   39   40   41   42   43   44   45   46   47   48   49   50   51   52   53   54   55   56   57   58   59   60   61   62   63   64   65   66   67   68   69   70   71   72   73   74   75   76   77   78   79   80   81   82   83   84   85   86   87   88   89   90   91   92   93   94   95   96   97   98   99   100   101   102   103   104   105   106   107   108   109   110   111   112   113   114   115   116   117   118   119   120   121   122   123   124   125   126   127   128   129   130

The engine 1 is adapted to be lubricated by

means of the construction described by what is known as splash lubricating whereby not only are the surfaces of 6 and 4 lubricated by oil thrown thereon by the revolution of 7 but oil is also carried by 6 and passes through the belts of ports 31, 32 and 33 for lubricating the surfaces of 4 and 2 and a portion of this latter lubricating oil may pass through a passage 43 to lubricate the lower end of valve 12 which, as before stated, normally is a close rotatable fit in its bearing.

It is of course obvious that the various methods of supercharging etc. described may be incorporated or not in an engine. For instance, the supercharging chamber 11 may or may not be used although I prefer to do so and also many variations occur in the application of the herein described principles but such applications are apparent to those skilled in the art and fully set forth in the appended claims.

It is apparent from the description also particularly that stratification may be had under certain conditions and also under other conditions a certain amount of turbulence may occur, both of which factors are of great advantage under predetermined conditions for efficient engine operation and for economy.

The relative strokes of pistons 6 and 5 may be in the ratio of about two to one but this may be varied to suit any particular design. In general, as before stated, the sleeve 4 with its connecting rod 9 is arranged to form a balance couple with the piston 6 and its connecting rod 8 and in this manner vibration is largely eliminated in the operation of engine 1.

Further, the arrangement of valve 12 being heated by the exhaust gases constitutes what is known as a "hot-spot" and the degree of heat imparted thereto by the exhaust gases will depend upon the position in which the exhaust gases are withdrawn from the interior of 4. The pressures under which the exhaust gases are withdrawn from the interior of 4 will depend upon the position, or degree of stroke, which will uncover passage 40 for filling 11 with hot gases under pressure. The chamber 11 may be separated by the web 14 into upper and lower compartments which may be suitably joined through passages in 14 (not shown).

I claim:

1. Means for stratifying a combustible mixture and exhaust gases in an internal combustion engine comprising an interior movable member adapted to inject a combustible mixture into the engine and eject exhaust gases from the engine to form only an upper stratum of combustible mixture and a lower stratum of exhaust gases.

2. In an internal combustion engine having an interior sleeve valve for controlling an inlet port and an exhaust port, a hollow rotat-

able valve for passing combustible mixture to the inlet port.

3. In an internal combustion engine having an interior sleeve valve for controlling a plurality of inlet ports and an exhaust port, a hollow rotatable valve for passing combustible mixture to the inlet ports. 70

4. In an internal combustion engine having an interior sleeve valve for controlling a plurality of inlet ports and an exhaust port, 75 a hollow rotatable valve having a plurality of ports for passing combustible mixture to the inlet ports.

5. In an internal combustion engine having a sleeve valve for controlling inlet and 80 exhaust ports, a chamber in said engine for retaining and releasing exhaust gases in accordance with the movement of the sleeve valve, and a hollow valve extending through said chamber to conduct explosive mixture to 85 said inlet ports.

6. An internal combustion engine having a sleeve valve, a compression chamber and a carburetor in combination with means to pass a combustible mixture from the carburetor to the compression chamber and thence in varying amounts to the interior of 90 the sleeve valve, and a piston connected to said valve for compressing the charge in said chamber. 95

7. An internal combustion engine having a sleeve valve, a compression chamber and a carburetor in combination with means to pass a combustible mixture from the carburetor to the compression chamber, where the 100 same is compressed at constant pressure, and thence in varying amounts to the interior of the sleeve valve.

8. An internal combustion engine having a sleeve valve, a compression chamber and a 105 carburetor in combination with means for passing and vaporizing liquid fuel from the carburetor to the compression chamber, means in said chamber for heating the mixture, and means for controlling the amount of 110 heated mixture delivered to said sleeve valve.

9. An internal combustion engine having a sleeve valve, a compression chamber and a carburetor, in combination with means for passing and vaporizing liquid fuel from the 115 carburetor to the compression chamber where the same is compressed at constant pressure and thence in varying amounts to the interior of the sleeve valve.

10. The combination with an internal combustion engine having a main piston, a combined sleeve valve and skirt piston and a carburetor, of a valve for controlling the passage of combustible mixture from the carburetor to the skirt piston and means between the 120 valve and skirt piston for controlling the passage of combustible mixture from the skirt piston through the sleeve where it is subjected to the action of the main piston. 125

11. The combination with an internal com- 130

bustion engine having a main piston, a combined sleeve valve and skirt piston and a carburetor of a valve for controlling the passage of combustible mixture from the carburetor to 5 the skirt piston and heated means between the valve and skirt piston for controlling the passage of combustible mixture from the skirt piston through the sleeve where it is subjected to the action of the main piston.

10 12. The combination with an internal combustion engine having a ported sleeve valve forming a combustion space, an air supply and a compression cylinder for the air of a chamber exterior to the sleeve valve, a passage 15 connecting the interiors of the sleeve valve and chamber and means to control said passage and regulate the air on its way from the compression cylinder to a sleeve valve port.

20 13. The method of charging and maintaining constant compression in an internal combustion engine which consists in compressing a combustible mixture and injecting the same into the engine, igniting the mixture in the 25 engine under further compression for producing a power stroke then withdrawing part of the ignited charge while under compression and injecting the same into the engine prior to the full compression of succeeding 30 injected combustible mixture for a succeeding power stroke.

14. The method of charging and maintaining constant compression in an internal combustion engine which consists in compressing 35 a combustible mixture at constant compression and injecting the same into the engine, igniting the mixture in the engine under further compression for producing a power stroke then withdrawing part of the ignited 40 charge and injecting the same into the engine prior to the full compression of succeeding injected combustible mixture for a succeeding power stroke.

15. In an internal combustion engine, a 45 cylinder, a piston therefor, a throttle member for introducing an explosive charge into each end of said cylinder, and means for adjusting said throttle member for introducing an explosive charge into one end only 50 of said cylinder.

16. In an internal combustion engine, a cylinder provided with intake and exhaust ports, a sleeve valve within said cylinder, means for operating said valve for opening 55 and closing said intake and exhaust ports, a

hollow valve for controlling the supply of explosive mixture to said cylinder, a rotary valve for controlling the flow of mixture to said hollow valve, and a piston adapted to reciprocate within said sleeve valve. 60

17. In an internal combustion engine, a cylinder, a sleeve valve for the cylinder, a piston for said cylinder, and a crank shaft for reciprocating said piston and valve in opposite phases whereby a balanced couple 65 will result in the reciprocation of said valve and piston.

18. In an internal combustion engine, a cylinder having a chamber within its walls and provided with a port, a piston reciprocating within said cylinder, and means for opening and closing said port for introducing a portion of the exhaust gases under pressure into said chamber and permitting the same to escape into said cylinder during the compression stroke of said piston. 75

19. In an internal combustion engine, a cylinder having intake and exhaust ports, a piston therefor, a heated chamber for containing an explosive mixture, means for compressing the mixture in said chamber, and means for opening said intake ports for receiving said mixture from said chamber into 80 said cylinder.

20. In an internal combustion engine, a 85 cylinder, a piston for said cylinder, and means for introducing an explosive mixture into said cylinder at a constant pressure at all engine speeds.

21. In an internal combustion engine, a 90 cylinder having intake and exhaust ports, a piston for said cylinder, a chamber for containing exhaust gases, said chamber having a port leading into said cylinder, means for opening said port at a predetermined position of said piston, and means for adjusting the effective size of said port. 95

22. In an internal combustion engine, a cylinder and a piston therefor, said cylinder having inlet ports at each end portion thereof and an exhaust port at its central portion, 100 said inlet ports opening toward the ends of said cylinder for directing the intake explosive mixture toward the ends of said cylinder for scavenging the same. 105

Signed at Wilmington, in the county of Los Angeles and State of California, this 26th day of July A. D. 1924.

CHARLES LAWRENCE STOKES.
